UNITED STATES PATENT OFFICE.

ASAHEL J. GOODWIN, OF BROOKLINE, MASSACHUSETTS.

COMBINATION INVALID BED AND CHAIR.

SPECIFICATION forming part of Letters Patent No. 453,236, dated June 2, 1891.

Application filed February 27, 1888. Serial No. 265,365. (No model.)

To all whom it may concern:

Be it known that I, ASAHEL J. GOODWIN, of Brookline, county of Norfolk, and State of Massachusetts, have invented an Improvement in Combined Invalid Beds and Chairs, of which the following description, in connection with the accompanying drawings, is a specification, like letters and figures on the drawings representing like parts.

This invention relates to beds especially adapted for hospital and invalid purposes, and has for one of its objects to construct the bed, as will be described, whereby the ends of the said bed may be raised and lowered independently of each other, to thus enable the position of the head and body of a patient or invalid supported by the bed to be changed without altering the position of the seat and legs of the patient, and vice versa.

Another feature of my invention consists in a stretcher to be used with the bed, so that the patient or invalid may be raised bodily up away from the bed.

My invention further consists in an independent seat portion having an adjustable foot-support connected thereto, the said seat portion being connected to the mattress and normally resting thereon to form part thereof, but adapted to be raised up away from the mattress to raise the seat and legs of the patient or invalid to obtain a different or easier position for the patient.

My invention still further consists in details of construction to be pointed out in the claims at the end of this specification.

Figure 1 is a top or plan view of an invalid-bed embodying my invention, the main or body portion of the stretcher being omitted to avoid confusion in the drawings; Fig. 2, a longitudinal vertical section of the bed shown in Fig. 1, looking in the direction indicated by the arrow; Fig. 3, a longitudinal sectional detail of the front portion of the bed, showing the foot-rest in a lowered position; Fig. 3^a, a detail to be referred to; Fig. 4, a transverse section of Fig. 2 on line x' x' to more clearly show the construction of the rack-bars; Figs. 5 and 5^a, details of one of the rack-bars; Fig. 6, a detail of the stretcher foot-rest; Fig. 7, a detail in elevation of the friction mechanism; Fig. 8, a section of Fig.

7 on line y y, the screws or bolts being shown in elevation; Fig. 9, a detail to be referred to; Fig. 10, a top or plan view of Fig. 9; Fig. 11, a detail showing the buckle by which the straps of the stretcher are secured in place; Fig. 12, a section of Fig. 11 on line y' y'; Figs. 13, 14, and 15, details to be referred to; Fig. 15^a, a detail of one of the lugs attached to the sides of the stretcher-frame; Fig. 16, a detail of the adjustable foot-rest; Fig. 17, a section of Fig. 16 on line y² y²; Fig. 18, a detail of the bar forming part of the foot-rest frame; Fig. 19, a section of Fig. 18 on line z z; Fig. 20, a detail in elevation of the ratchet mechanism governing the movement of the foot-rest secured to the seat portion of the mattress; Fig. 21, a top or plan view of Fig. 20; and Fig. 22, a sectional detail to be referred to, the section being taken on line z' z', Fig. 20.

Referring to Figs. 1 and 2, the head-board A of the bed, having secured to it the sides A' A², provided with legs A³ at their opposite ends, is herein shown as made in two parts, 75 as 2 3, united by hinges, as 4, the said parts being normally locked in their upright position by a rod a, (see Fig. 2,) secured at one end to a cross-bar a¹, and threaded at its other end, and inserted through a forked lug 8c a² on a cross-bar a⁴, after which the rod receives a nut a'.

The side boards A' A² have secured to them brackets or castings a³, (see Figs. 3^a and 2,) each having a flange a⁴ and gib a⁵, made adjustable, as shown, by set-screws a²⁰, the said flange and gib constituting guides for a rack-bar or brace a⁶. Each rack-bar, as herein shown, is slotted at its lower end (see Figs. 4 and 5) to form ears a⁷, which embrace a cross-bar a⁸, as shown in Fig. 4, each rack-bar being kept seated on the bar a⁸ by a pin a⁹, the said pin forming, as it were, a pivotal connection between the said cross-bar and rack-bar. Each rack-bar a⁶ is provided with a web 90 or flange a¹⁰, having a foot a¹¹, which is also slotted to fit over and engage the edge of the said cross-bar a⁸, the said foot being also tapped and threaded to receive an adjusting-screw a¹³, by which the rack-bar may be turned 100 on the stud a⁸ as a pivot, to thereby move the upper end of the rack-bar outward, the said

rack-bars forming adjustable braces to support a stretcher-frame, to be described. The rack bars or braces a^5 have their upper ends fitted into and firmly secured to brackets or castings b , fastened to the side bars or rails b' of what is denominated a "stretcher-frame," the said brackets or castings being located, substantially as shown, upon the said bars or rails, so that when the rack-bars are moved vertically, as will be described, the stretcher-frame will also be moved bodily up or down.

The side bars or rails b' of the stretcher-frame are provided at their ends, near the head-boards, with castings $b^2 b^3$, (see Figs. 1, 15 13, and 14,) each casting preferably having secured to its inner face a layer b^4 of felt or other material to prevent marring or injury to the wood-work outside of it when the stretcher-frame is moved up and down by the 20 rack-bars.

The side bars of the stretcher-frame, near the head of the bed, are united, preferably, by a cross-bar b^5 , having at its opposite ends castings provided with lugs b^6 , preferably elongated, as shown in Figs. 14 and 15. The casting b^2 (shown separately in Fig. 15^a and having an elongated slot, as b^x) is entered by one of the lugs, and thereafter the bar b^5 is given a quarter-turn, so that the lug b^6 stands with 30 its longest portion across the said slot b^x , and then the lug b^6 at the opposite end of the said bar b^5 is made to enter the opening in the casting b^3 and pass therein beyond the end of a locking device b^7 , (shown in Figs. 13 and 14 35 as a spring,) the latter holding the bar in place.

Each side rail b' has secured to it, preferably near the longitudinal center of the bed, a boss b^{10} , (see Fig. 2,) forming a bearing for 40 a stud on the ends of a substantially $\sqcup$ -shaped bar b^{13} , of a length substantially equal to the distance between the said bosses and the head-board. The $\sqcup$ -shaped bar b^{13} in practice will be covered with canvas or other suitable or textile material b^{24} , the said bar and covering forming part of the stretcher and constituting a movable support for the body and head of the patient.

The body-supporting frame has its free end 50 sustained, as shown, by the cross-bar b^5 , so that when the stretcher is raised bodily through the rack-bars the head of the patient is raised at the same time as the body—that is, the entire body of the patient is raised at 55 one time.

The side rails b' have secured to them the foot-supporting portion of the stretcher, (see Figs. 2 and 6,) it consisting of a substantially $\sqcup$ -shaped frame b^{14} , covered with canvas or 60 other suitable material, as b^{25} , the said frame being secured to the side rails, as shown, by castings b^{15} , fastened to the ends of the frame and having arms b^{16} , (see Figs. 2 and 6,) shaped substantially, as best shown in Fig. 6, to enable the said arms to be slid under and so as 65 to engage the upper and lower sides or edges of the side bars b' of the stretcher-frame, the

main casting b^{15} resting upon the top of the side bar or a rail thereon. This construction enables the foot portion of the stretcher to be 70 readily removed and put on, as desired.

The casting b^{15} is preferably lined with felt or other material to prevent marring of or injury to the side bars. I do not desire to limit my invention to the exact form of casting b^{15} shown in Fig. 6, but may use any well-known equivalent-shaped clasping device rigid yet readily detachable from the side bars.

The portion of the stretcher between the 80 foot and back supporting sections will preferably be composed of a number of strips c of canvas or other material, (see Fig. 12,) the said strips being extended through slots c^x in the side rails and firmly secured in place, as 85 shown, by buckles c^2 , herein shown as a plate of metal secured to the side bars preferably by staples c^3 , (see Figs. 11 and 12,) the said plate having teeth c^4 to engage the strips of canvas or other material. The inner side of 90 the top rail of the stretcher-frame is grooved or channeled at c^x , as shown in Fig. 12, so that as the buckle c^2 is moved into its upright position substantially parallel to the side rail the teeth c^4 are made to enter farther into the 95 material, thus obtaining a sure and reliable fastener for the said strip.

The rack bars or braces a^5 are engaged by pinions 25, only one being shown in Fig. 2, on a shaft 26, having mounted thereon a gear 100 27 in mesh with a pinion 28 on a hub or hollow shaft having mounted thereon a disk 29, comprising part of a friction mechanism to be hereinafter more fully described in connection with the head-section of the bed, 105 where like devices, but designated by different letters, are employed to adjust and hold the toothed sector c^{12} .

The sides $A' A^2$ have pivotally secured to them a mattress-supporting frame composed 110 of a head and a foot section.

The head section is herein shown as a substantially $\sqcup$ -shaped frame c^5 , having at its ends a sleeve or hub to engage a stud c^6 on the casting a^3 , (see Fig. 2), and secured thereto, as shown, by a washer c^7 , riveted thereon. Each arm of the $\sqcup$ -shaped frame c^5 comprising the head-section is provided, as shown, with a stud or roller c^8 , extended into the slot c^9 of an arm c^{10} , forming part of a toothed 120 sector c^{12} , mounted on a stud or arbor c^{13} of a casting c^{14} , secured to the sides $A' A^2$. The sector c^{12} meshes with and is driven by a pinion d on a shaft d' , having mounted thereon a gear d^2 in mesh with a pinion d^3 on a hollow shaft d^4 having secured thereto or forming part thereof, as shown, a friction-disk d^5 , (see Figs. 2, 7, and 8,) the said hollow shaft being supported in bearings d^6 , forming part of a casting d^x , secured to one side board, as 130 A^2 . The friction-disk d^5 has co-operating with it spring-arms $d^7 d^8$, provided with suitable friction-surfaces d^9 , to bear against the disk d^5 , the said disk and spring-arm consti-

tuting a friction mechanism by which to maintain the shaft d^4 stationary in any desired position. Each spring-arm referred to is slotted at its end, as shown in Fig. 7, to enable 5 gage a threaded hub d^{10} on a bolt d^{12} , and is provided with a hole near its opposite end, through which is extended a bolt d^{13} , inserted into a threaded socket d^{14} in the casting d^8 . The spring-arm d^8 bears against the casting d^8 and the spring-arm d^7 against the head of the bolt d^{13} , so that by turning the said bolt the amount of friction between the spring-arms and disk may be varied, as desired.

The foot-section of the bed is composed as herein shown of a substantially L-shaped frame e , preferably of sheet-steel of angle form, the bent corners of the L-shaped frame being provided with braces e' to unite the sides or arms e^2 to the main or cross piece of the frame. (See Fig. 18.) Each arm e^2 has secured to it, by rivets or otherwise, a sector-gear e^3 , (see Figs. 2 and 3,) having a cam-surface, as e^4 , with which co-operates a roller e^5 , fastened to a bending-bar e^6 , to be described. Each sector-gear e^3 is driven by a pinion e^7 on a shaft e^8 , having mounted thereon at one end, as shown, a gear e^9 in mesh with a pinion e^{10} on a hollow shaft or hub e^{12} , provided with a friction-disk e^{13} , the said friction-disk 25 being engaged by spring-arms e^{14} in a similar manner to that described with the friction-disk d^5 of the head-section. The arms e^2 of the frame composing part of the foot-section at their ends opposite to the sector-gears are 30 engaged by channel-bars f , (see Fig. 16,) which are adapted to slide over the said arms to extend or lengthen the foot-section, as will be described. Each channel-bar f , as shown in Fig. 17 on an enlarged scale, has a stud f' , 35 which is engaged by one of a series of holes f^x (see Fig. 16) in a lever f^2 , pivoted at f^{20} (see Fig. 3) to the sides $A' A^2$, the said lever being secured to the channel-bar, as shown, by a spring-catch f^3 , shown as a flat spring 40 pivotedly secured to the channel-bar by screw f^4 , and having a stud or projection f^5 to enter a socket or recess in the stud f' . The channel-bars f sustain the foot-rest, consisting of arms f^6 and foot-board f^7 , supported 45 thereby, (see Figs. 2 and 16,) the said arms being pivoted to the said channel-bars, as at f^8 , and provided with notches $f^9 f^{10}$, (see dotted lines, Fig. 16,) to co-operate with studs $f^{12} f^{13}$ on the channel-bar to form stops by which 50 the backward or outward movement of the foot-rest is limited. The foot-rest is retained in its normal position, as shown by full lines, Fig. 16, by a catch or locking device, shown as a spring f^{14} , pivoted to one of the arms f^6 , 55 and having a pin or stud f^{15} to enter holes in the said arm and channel-bar. The foot-rest is turned into its dotted-line position, Fig. 16, when not in use, and it is locked in its dotted-line position by the stud f^{15} on the spring f^{14} entering a second hole in the channel-bar. As shown in Figs. 3 and 16, the last hole f in the lever f^2 is in engagement with the stud

f' on the channel-bar, thus bringing the foot-rest in its farthest position from the bed. To shorten or bring the foot-rest nearer the bed, 70 the stud f^5 is disengaged from the socket in the end of the stud f' , and the channel-bars f moved up on the arms e^2 and another hole f^x engaged with the stud f' .

The head and foot rest sections sustain the suspension-mattress, composed, preferably, of end springs g and links g' , secured to plates or disks g^2 . Near the longitudinal center of the mattress and on opposite sides thereof two links, as t , (see Fig. 1,) are made, as herein shown, of considerable thickness to obtain strength, each link being provided, as shown, with a stud t' , to which the hair or other mattress (not shown) is secured. The plates or disks g^2 , substantially in line with the pivots c^7 of the head-section, are joined by stays or chains g^3 (see Fig. 2) to a cross-bar g^4 , secured, as shown, to the casting c^{14} . Two links $t^2 t^2$, also in line across the mattress and adjacent to the bars $t t$, are made stronger, and are provided outside the mattress with studs 78, upon which are fitted the slotted ends of side bars g^5 , extended toward the foot of the bed and joined at their ends by a shaft or rod g^6 , having bearings in the said side bars. The shaft 85 or rod g^6 and side bars g^5 form a supporting-frame for an auxiliary seat, composed, as shown, of strips or slats g^7 , preferably of sheet metal, having one end bent around the shaft or rod g^6 and the other end engaging the bars 90 t^2 and links in line therewith; but, if desired, the said seat may be made of canvas or wire-netting or other material. The auxiliary seat-frame is raised and lowered, as shown, by a windlass composed of a substantially L-shaped bar or frame g^8 , having holes at its ends, which are fitted upon studs 9 on the side bars g^5 , and of one or more chains or ropes g^{10} , connected to the cross-bar g^9 of the L-shaped bar g^8 and to a shaft g^{12} , supported 95 in bearings secured to the sides $A' A^2$, as shown in Fig. 2. The arms of the L-shaped bar g^8 are detachably connected to the side bar g^5 by levers g^{13} , pivoted to said arms and adapted to engage the studs 9. The shaft g^{12} 100 is preferably provided at one end with a pinion or ratchet k , normally engaged by a weighted or gravitating pawl k' , (see Figs. 2, 3, 9, and 10,) having a spring arm or extension k^2 , preferably of sheet-steel, the said spring-arm being engaged by a stud k^3 on a friction-lever k^4 , pivoted to one of the side boards, as A^2 . Normally the pawl k' is in engagement with the ratchet k , as shown in Figs. 2 and 3, and the friction-lever k^4 will be in the dotted-line 105 position shown in Fig. 3; but if it is desired to disengage the pawl from the ratchet the friction-lever k^4 will be turned into the position shown by full lines in Figs. 2 and 3, the said lever then exerting a pressure on the 110 spring arm or extension k^2 , so that when the shaft g^{12} is turned but very little, or a sufficient distance to disengage the pawl, the said spring-arm will act to throw the pawl out of 115

engagement with the ratchet, thus permitting the shaft to be rotated in either direction.

In most cases I prefer to employ a friction mechanism comprising a disk and spring-arms, as described; but in every case where I have herein shown and described such a friction device I may employ therewith, if desired, the pawl and spring-extension actuated by the friction-lever, it being especially applicable to the center and seat portion when the invalid is a heavy person and the attendant of but medium or little strength, the said parts being readily applied to and detached from the bed. The shaft or rod g^6 has mounted on it a foot-supporting frame or leg rest composed of sides r and a cross-bar r' , the said sides having secured to them, as shown, hubs r^2 , (see Fig. 22,) through which the shaft or rod g^6 is extended. The shaft or rod g^6 has secured to it at one end beyond the side bar g^5 a ratchet-wheel r^3 , engaged by a pawl r^4 , pivoted to the side bar g^5 , the said pawl being normally held in engagement with the said ratchet by a friction-lever r^5 , pivoted to the side bar g^5 , the said pawl and friction-lever normally occupying the full-line position shown in Fig. 20. The friction-lever is shown as provided with a V-shaped end, which forms two ears or flanges r^6 r^7 , extended with relation to the length of the said lever, one ear, as r^6 , acting on one side of a beveled arm r^8 of the pawl to keep the said pawl in engagement with the ratchet, as shown by full lines, Fig. 20. When it is desired to release the pawl r^4 from the ratchet the friction-lever is turned on its pivot to bring the ear r^6 in engagement with the arm r^8 of the pawl, so that when the leg-rest is lifted a very little the ear r^6 will slip down the beveled or V-shaped arm of the pawl and turn the said pawl into its dotted-line position, out of engagement with the ratchet, thus permitting the leg-rest to be moved readily in either direction.

The ratchet and pawl and friction-lever r^5 constitute a locking device for the foot-supporting frame.

In practice the foot-supporting frame or leg-rest will preferably be equal to substantially one-half the width of the seat, so that in case of injury to one leg of a patient, the said injured leg may be supported in any desired or comfortable position upon the leg-rest, while the well leg of the patient may hang over the shaft g^6 . This is especially true when the seat and leg-rest are raised into substantially the position shown in Fig. 2, and the head-section has been raised substantially into the dotted-line position Fig. 2, the said seat and head sections, when in the positions described, forming a chair.

As shown in Fig. 1, the foot-supporting frame or leg-rest is in position to receive the right leg; but, if desired, the said frame may be moved to receive the left leg, the shaft g^6 being first unclamped from one of the side bars g^3 and the slats g^7 disengaged from the

said shafts, and then engaged again when the supporting-frame has been moved into position. The bending-bar e^6 (see Fig. 2) is provided at its ends with arms s , supporting rollers e^5 , which rest upon and ride over cam-surfaces e^4 of the segments e^3 , before described, the said cam-surfaces being so shaped that the bending-bar, is in its lowest position 75 (shown in Fig. 2,) when the foot-supporting frame is in its highest position, and vice versa, as shown in Fig. 3. The longitudinal links forming that portion of the wire mattress immediately above the bending-bar are 80 replaced by short chains s' , which enable the mattress to be bent over the bending-bar when the foot portion is lowered into the position shown in Fig. 3.

In practice the head-section may be raised 85 from its full to its dotted line position, and vice versa, from the side of the bed by means of a crank not shown, but which is applied to the hollow shaft or hub d^1 , and the foot-section may be turned in a like manner from the 90 position shown in Fig. 2 to that shown in Fig. 1, and vice versa, and the seat portion may be raised and lowered by turning the shaft g^{12} . When the foot-section is raised from the position shown in Fig. 3 to that shown in Fig. 95 2, the channel-bars f will be moved outwardly by the levers f^2 to lengthen the said foot-section, and the foot-rest will be brought toward or nearer to the bed when the said foot-section is moved into the position shown in 100 Fig. 3.

My improved invalid-bed may be transformed into a chair by moving the head-section into its dotted-line position, Fig. 2, and the foot-rest and section into substantially 105 the position shown in Fig. 3, the auxiliary seat being in its lowest position—that is, resting on the mattress—or the said bed may be transformed into a reclining-chair by raising the auxiliary seat into the position shown in 110 Fig. 2, the head-section being in its dotted-line position.

When it is desired to employ the stretcher to raise the patient up from the bed to enable the latter to be made or for other purpose, 115 the strips c , comprising the seat portion of the said stretcher, may be first passed under the patient and secured to the side rails. The patient may then be raised into a sitting posture to enable the back-supporting frame 120 to be secured in place, its end resting, as shown, on the cross-bar b^5 . The stretcher-frame is now raised through the rack-bars a^5 by rotating the pinion 28 by the crank referred to. It will be noticed that as the 125 stretcher-frame is raised the patient is lifted bodily at one time. The body-supporting section of the stretcher may be inclined by raising the head-section of the bed until it forms a bearing against the under side of the 130 said body-supporting section, (indicated by dotted lines, Fig. 2.)

To facilitate shipping, the part 2 of the head-board may be folded down over the bed—that

is, substantially at right angles to the part 3— and the foot-rest turned into its dotted-line position shown in Fig. 16. By means of the adjusting-screws a^3 the rack-bars may be 5 turned on the stud a^8 as a pivot, and their upper ends moved outward to take up any spring in the bar a^9 and maintain the side rails of the stretcher-frame rigid and the material comprising the stretcher taut when the 10 said stretcher is used to sustain a substantially heavy person, thus obviating any considerable sagging of the stretcher.

I do not herein claim, broadly, a pivoted leg-support and sliding foot-rest connected to 15 a frame, as the same forms the subject-matter of another application, Serial No. 311,305, filed by me May 18, 1889. It is obvious that when the head-section is elevated and the foot-section lowered the bed constitutes an invalid- 20 chair.

The sliding foot-rest herein shown and described is not herein claimed broadly, as it forms a subject-matter of another application, Serial No. 311,305, filed May 18, 1889.

25 I claim—

1. In an invalid-bed, side bars A^2 , means to support them, head and foot sections pivotally mounted with relation to the said side bars, a suspension-mattress connected at its 30 ends to the said head and foot sections, channel-bars having an attached foot-rest and adapted to slide on the bars of the foot-section, and a link f^2 , connected to the said channel-bars and to a fixed part of the bed-frame, 35 combined with a slotted cam to receive a roller or other stud c^8 on the head-section and independent gearing to actuate the said slotted cam, and also the said foot-section, either one separately, as and for the purposes 40 set forth.

2. In an invalid-bed, the combination, with the sides of the bed-frame, and a head-section, a foot-section, and a bending-bar, each pivoted independently of the other upon or with 45 relation to the said sides, of a suspension-mattress secured to the said head and foot sections and means to actuate the said head and foot sections and bending-bar, to operate substantially as described.

50 3. In an invalid-bed, a stretcher-frame consisting of side rails b^1 , having castings b^2 , and a cross-bar b^5 , detachably secured thereto, and having lugs b^6 , combined with a locking device to retain the said lugs in place in the 55 said castings, substantially as described.

4. In an invalid-bed, a stretcher-frame consisting of side rails and a cross-bar joining the said side rails near the head of the bed, combined with a body-supporting frame 60 adapted to rest upon and be supported by a part of the said stretcher-frame, and with a foot-support detachably secured to the ends of the said side rails, substantially as described.

65 5. In an invalid-bed, the combination, with a stretcher-frame composed of side rails having slots, as c' , and top rails provided with

grooves or chambers on its under side in line with the said slots, of an intermediate or seat-sustaining section composed of strips of textile material, and buckles pivotally secured to the side rails and adapted to force the material up into the said grooves in the top rail, substantially as described.

70 6. In an invalid-bed, side bars, a pivoted head-section provided with a stud or roller c^8 , a pivoted foot-section, a suspension-mattress connected to the said head and foot sections, means to move the said foot-section, and a slotted arm into which is entered the said stud or roller c^8 , and means to move the said slotted arm to actuate the said head-section, the slotted arm serving to prevent the head-section from being drawn forward by the suspension-mattress, substantially as described.

75 7. In an invalid-bed, the head-section provided with a stud or roller c^8 , combined with a slotted arm having a toothed sector, and into the slot of which the said roller is extended, the pinions $d^2 d^3$ to move the sector, 80 and a locking device for said pinion d^3 to hold the head-section in adjusted position, substantially as described.

85 8. In an invalid-bed, the combination, with the sides of the bed-frame, of head and foot sections pivoted to said sides, a suspension-mattress connected to said head and foot sections, and an independent auxiliary seat-frame and its seat pivotally connected to the suspension-mattress, substantially as de- 90 scribed.

90 9. In an invalid-bed, the combination, with the sides of the bed-frame, of head and foot sections pivoted to said sides, a suspension-mattress connected to said head and foot sections, an independent seat-frame and its seat pivotally secured to the suspension-mattress, and an adjustable foot portion secured to the auxiliary seat-frame, substantially as de- 100 scribed.

105 10. In an invalid-bed, the combination, with the sides of the bed-frame, of head and foot sections pivoted thereto, a suspension-mattress secured to the head and foot sections, an auxiliary seat-frame pivotally connected 110 to said suspension-mattress and provided with a seat, a lifting-frame secured to the seat-frame, and means to raise and lower the said auxiliary seat-frame, substantially as de- scribed.

110 11. In an invalid-bed, head and foot sections, a suspension-mattress supported thereby, and an auxiliary seat-frame consisting of side bars g^5 and shaft g^6 , combined with a leg-rest secured to said shaft, and a locking 115 device to secure the leg-rest in adjusted position, and with a releasing device for the said locking device, substantially as de- scribed.

120 12. In an invalid-bed, head and foot sections, a suspension-mattress supported thereby, and an auxiliary seat-frame consisting of side bars g^5 and shaft g^6 , a ratchet on said shaft, a pawl to engage said ratchet, and with

a spring, as r^5 , to act on the said pawl, substantially as described.

13. The combination, with a shaft having a pinion or ratchet, of a gravitating pawl to engage said ratchet, a spring-arm, as k^2 , secured to said pawl, and a lever, as k^4 , to act on the spring-arm and disengage the pawl from the pinion or ratchet on a slight rotation of the said shaft, substantially as described.

14. The combination, with the foot-section and bending-bar, of the lever s , the cam, and mechanism for operating the cam to raise and lower the said bending-bar toward and from the mattress, whereby the bending-bar acts to bend the mattress when the foot-section is lowered, substantially as described.

15. In an invalid-bed, the vertically-movable stretcher-frame having side rails, combined with the detachable horizontally-extended foot-section having castings b^{15} , substantially as described, to embrace or engage the said rails, substantially as described.

16. The combination, with the side bars, as b' , of rack-bars or braces connected thereto and provided with feet, as a^{12} , a cross-bar joining said rack-bars at their lower ends, and means to operate said rack-bars, substantially as described.

17. The combination, with the side bars, as

b' , of rack bars or braces connected thereto 30 and means to operate said rack-bars, with a cross-bar joining the said rack-bars at their lower ends, and an adjusting-screw for each rack-bar, to operate substantially as described.

35

18. In an invalid-bed, the combination, with a mattress having rigid links or castings t^2 at each side, of an auxiliary seat having a supporting-frame, the said frame being pivotally connected to the said rigid links, the seat being connected to the mattress between said links, substantially as described.

40

19. In an invalid-bed, the combination, with the sides of the bed-frame, of an extensible foot portion consisting of a frame provided 45 with a segmental gear and having arms e^2 , channel-bars to engage and slide upon the said arms, a pivoted foot-rest and a locking device to secure the said foot-rest in flat or extended position, and gearing to engage said 50 segmental gear, substantially as described.

In testimony whereof I have signed my name to this specification in the presence of two subscribing witnesses.

ASAHEL J. GOODWIN.
